UNITED STATES PATENT OFFICE.

BENJAMIN ROSENBERG, OF NEW YORK, N. Y., ASSIGNOR TO WILLY MAYER,
OF SAME PLACE.

DESIGN FOR A NAIL-FILE AND HOLDER.

SPECIFICATION forming part of Design No. 33,678, dated December 11, 1900.

Application filed August 2, 1900. Serial No. 25,722. Term of patent 7 years.

To all whom it may concern:

Be it known that I, BENJAMIN ROSENBERG, a citizen of the United States, and a resident of New York city, in the county and State of New York, have invented and produced a new and original Design for a Nail-File and Holder, of which the following is a specification.

Figure 1 is a side elevation of a nail-file and holder, showing my new design. Fig. 2 is a perspective view of the same, showing certain features of the design not shown in Fig. 1.

As shown in the drawings, the nail-file blade 1 is provided on each side thereof with the usual transverse file-blades or serrations 2 and at the extremity thereof with the cuticle knife or blade 3, which is flat on one side and is slightly convex on the other side. The holder 4 is of an elongated cylindrical form, having a diameter which is uniform throughout its length and slightly greater than the width of the blade 2. The end 5 of the holder where it is joined with the blade 2 is closed 25 by a convex portion 5, as seen in Fig. 1. The

holder is provided at about the central portion with an annular rib or projection 6, which is serrated or knurled on its outer surface, as indicated. The holder is tubular in form, open at the end opposite the file-blade, and 30 is provided with a longitudinally-extending slot 7, terminating in a small circular opening 8, as shown in Fig. 2.

The nail-file is provided with file-blades or serrations 2 without any interruption throughout its length from the cuticle knife or blade 3 to the convex portion 5 of the holder 4.

Having described my invention, what I claim as new, and desire to secure by Letters Patent, is—

The design for a nail-file and holder, as herein shown and described.

In testimony whereof I have signed my name to this specification in the presence of two subscribing witnesses.

BENJAMIN ROSENBERG.
